DRAINBOARD

Julian L. Perkins, West Springfield, Mass.

Application July 21, 1936, Serial No. 91,680

5 Claims.

(Cl. 68—32)

This invention relates to improvements in clothes wringer apparatus and is directed more particularly to improvements in drain boards for wringers.

The principal objects of the invention are directed to the provision of a drain board structure for a wringer wherein a drain board is pivoted to a wringer so it may be swung away from the rolls and it has a lower drip board with an upper apron or guide for guiding clothes into and between or away from the rolls of the wringer. As a special feature of the invention the apron is of such a nature as to permit water to flow therethrough and onto the drip board when the clothes are passed between the wringer rolls or are being fed therefrom.

Various other novel features and advantages of the invention will be hereinafter more fully referred to in connection with the accompanying description of the present preferred form thereof.

In the drawing:

Fig. 1 is a transverse sectional elevational view through a wringer and showing the novel features of the invention associated therewith;

Fig. 2 is a side elevational view of a wringer showing the drain board construction of the invention associated therewith;

Fig. 3 is a fragmentary inverted plan view to explain certain features of the invention; and

Fig. 4 is a fragmentary perspective view to illustrate certain details of construction.

Referring now to the drawing more in detail, the invention will be fully described.

The novel features of the invention are adapted for use in connection with wringers of various forms. A typical wringer is shown for purposes of description, and has end frames 2 and rolls 4 and 6' journaled therein, and the said end frames are tied together in some suitable manner as by a longitudinal bar member 6.

The end frames and longitudinal bar member, or such other connecting means between the said frames as may be desired, will provide a strong, rigid structure for the rolls. To this frame structure, which will be hereinafter referred to as the frame, the drain board structure of the invention is attached, preferably for swinging movements thereto.

A drain board of the invention indicated by 10 is disposed at either side of the wringer and being alike, one only will be described in detail.

The drain board 10 preferably consists of a frame which has end portions 12, an upper longitudinal portion 14 and a lower longitudinal portion 16. The end portions 12 are formed as in

Fig. 1 to project upwardly from the wringer and then inwardly so that the end portions are connected to the lower longitudinal portion.

The upper ends of the end members 12 are turned inwardly and downwardly as shown at 18, so that the upper longitudinal member 14 is connected to the upper ends of the end members 12. The frame may be of wire or rod for purposes of economy in manufacture and for lightness.

A drip board 20 has its ends secured to the end members of the frame and is disposed to incline downwardly as shown more clearly in Fig. 1. An apron for guiding the clothes into the rolls and for receiving them as they are delivered by the rolls is provided above the drip board. According to one feature of this invention, the said apron is of such a nature that water may pass therethrough and fall onto the drip board below.

To this end, a plurality of wires or rods 24 extend from the upper longitudinal frame member 14 outwardly and downwardly and have their lower ends secured to a longitudinal member 26. The ends of member 26 are secured to end members 12.

It may here be stated that the various elements may be secured together by brazing, welding or in any other suitable way, all to the end that there is provided a strong, rigid structure which is light in weight.

The drain board is secured to the wringer frame for swinging movements preferably at its lower side so that the upper portion may be swung away from the wringer rolls. To this end, plates 30 such as shown in Fig. 3 are secured by bolts 32 or the like to the longitudinal member 6 which have their ends 31 turned upwardly and then downwardly to provide longitudinal slots or bearings having open sides disposed downwardly. The drip board is cut away as at 34 to expose hinge parts 17 of longitudinal member 16 there being a member 30 at or near each end of the longitudinal member 16.

The hinge parts 17 of the member 16 are receivable in the sockets of members 30 and the parts function to permit the drain board to swing so its upper side may swing towards and away from the rolls. The drain board is mounted on the frame by moving it upwardly so the hinge parts 17 enter the sockets of members 30 at each end of the longitudinal member 6.

To retain the drain board or boards in operable position, spring means is provided. This preferably consists of one or more spring members such as shown in Fig. 3 and has loops 40 ar-

ranged to yieldingly bear on the lower side of the drip board 20. Intermediate coiled portions 42 are carried by projections 44 of a plate or plates such as 46 secured to the under side of the longitudinal frame member 6.

The spring device is so made that the loops 40 bear against the under side of the drip boards and yieldingly hold them in position, yet the drain board may be tilted outwardly against the 10 spring or springs. By moving a loop 40 away from the drip board, the longitudinal members 16 may be dropped from the sockets of the members 30 to facilitate the drain board being removed from the wringer.

15 It will be observed that the drain board is so constructed that water is conducted by the lower drip board away from the wringer and that the apron facilitates the guiding of the clothes to or away from the rolls, while any water there- 20 in falls through the apron and onto the lower drip board. Should the material being passed into the wringer become jammed, the drain board may be tilted forwardly away from the rolls to facilitate the ready and easy removal of the 25 material.

To facilitate water being conveyed onto the drip board, there is provided a drip board 50 below the lower roll which has end parts 52 that are pivoted as at 54 to the end frames. The piv- 30 otal connections facilitate this drip board being tilted in one way or the other. As shown in Fig. 1 the board 50 is tilted so as to direct water onto the drip board at the left.

While I have described the invention in great 35 detail and with respect to a preferred form thereof, it is not desired to be limited thereto since many changes and modifications may be made therein without departing from the spirit and scope of the invention.

40 What it is desired to claim and secure by Letters Patent of the United States is:

1. The combination with a wringer frame of, a drain board including a lower drip board and an

5 apron thereabove provided with openings therethrough spaced substantially throughout its surface, and connections between said drain board and wringer frame, the said openings being bounded by spaced apron-forming members.

2. The combination with a wringer frame of, a drain board having a lower drip board and an apron thereabove provided with openings therethrough spaced substantially throughout its surface, and connections between said drain board and wringer frame, the said connections consisting of parts associated with the drain board pivoted in parts associated with the wringer frame whereby the said board may be swung relative to said frame.

10 3. The combination with a wringer frame of, a drain board having a lower drip board and an upper apron thereabove provided with openings therethrough spaced substantially throughout its surface, sockets on said frame, hinge parts on 20 said drain board removably and pivotably disposed in said sockets, and spring means acting on said drain board yieldingly holding the hinge parts in said sockets whereby the drain board may swing relative to said wringer.

25 4. A unitary drain board comprising in combination, a frame including end and longitudinal members, the end members being disposed in different planes, a lower drip board secured to said members, and spaced bars extending transversely above and over the drip board secured to the longitudinal members forming a drain board provided with openings substantially throughout its surface.

30 5. A unitary drain board comprising in combination, a frame having spaced end members extending forwardly, upwardly and rearwardly, longitudinal members extending between and connected to the first-named members, a drip board secured to said members, and an apron above and over the drip board formed by spaced bars secured to the longitudinal members.

40 JULIAN L. PERKINS.
